UNITED STATES PATENT OFFICE.

JOHN A. ANTHONY, OF CHARLESTON, SOUTH CAROLINA.

BRAKE-OPERATING DEVICE.

1,109,501.

Specification of Letters Patent.

Patented Sept. 1, 1914.

Application filed April 23, 1913. Serial No. 762,069.

To all whom it may concern:

Be it known that I, JOHN A. ANTHONY, a citizen of the United States, residing at Charleston, in the county of Charleston and State of South Carolina, have invented new and useful Improvements in Brake-Operating Devices, of which the following is a specification.

The present invention relates to brake operating devices.

In carrying out my invention it is my purpose to provide a simple, cheap and effective device which is arranged adjacent one side of the railroad track and which may be operated by a semaphore or by a suitable lever and which is adapted to co-act with suitable mechanism upon an engine or coach that is supplied with an air-brake system, and which is adapted to open a normally closed valve to bleed the air pipe and to apply the brakes.

A further object of the invention is the provision of brake operating mechanism which includes a valve connected with the train pipe of the air-brake system, and which is provided with an extending stem upon which is arranged a longitudinally adjustable throw arm that is provided with a vertically adjustable member whereby the said arm may be properly adjusted, so that the said throw arm is properly positioned for contact with a striker arm ranged to one side of the track and slid into operative position either manually or automatically by the operation of a semaphore.

A further object of the invention is the provision of means arranged upon a striker arm which is adapted to coöperate with a throw arm arranged upon the stem of an air bleed or outlet valve which is connected with an air-brake system, whereby the sliding movement of the striker arm will be regulated, so that the same cannot be moved beyond proper contacting position with relation to the throw arm, so that the said striker arm will not contact with any part of the engine or coach and be injured by such contact.

With the above recited objects in view, and others which will appear as the nature of the invention is more fully understood, the improvement resides in the construction, combination and operative arrangement of

parts set forth in the following specification and falling within the scope of the appended claim.

The essential features of the invention involved in carrying out the objects above indicated, are necessarily susceptible of embodiment in various forms of construction without departing from the scope of the invention, but certain preferred and practical embodiments are exemplified by the accompanying drawings, in which:

Figure 1 is a side elevation of the portion of an engine to which my improvement is attached, and illustrating the throw mechanism arranged to one side of the track, Fig. 2 is a detail transverse sectional view taken approximately on the line 2—2 of Fig. 1, Fig. 3 is an enlarged longitudinal sectional view taken through the bleed or air exhaust valve and the throw arm attached to the stem of the valve, Fig. 4 is an enlarged sectional view taken through the line 4—4 of Fig. 2, Fig. 5 is a detail perspective view of a portion of the stem of the valve, Fig. 6 is an enlarged view of the valve, and Fig. 7 is a detail section upon the line 2—2 of Fig. 3.

As is well known to railroad men the semaphore signals in inclement and hazy weather are at times hardly discernible by the engineer, and as a consequence fatal wrecks have occurred. There are other conditions which have been known to exist wherein the engineer makes a mistake in the signals and does not apply the brakes in time to avert a collision with a train within his block, among which may be cited, the sticking or nonworking of the engineer's valve; the disconnection of the throttle; the apprehension of the engineer that he has already operated the valve, and other such like circumstances which result in head-on, rear-end or side-wipe collisions and the resultant fatalities to the train crew and passengers.

It is to be therefore considered the primary object of the present invention to provide means whereby, when occasion arises, the brakes will be properly applied without necessitating the operation of the engineer's valve, said mechanism being so arranged upon the exterior of the engine or upon a coach as to prevent the same being inter-

ferred with by the crew or passengers when the train is in motion.

In reducing my improvement to practice, I provide the main air pipe of the train line 5 with a T-coupling 1, the same being provided with a branch pipe 2 having a regulating valve 3 and having a bleed or exhaust valve 4. The mechanism is attached at any convenient point to any self-propelled vehicle, but in the showing of the drawings I have illustrated the same applied to a locomotive engine. The bleed valve 4 may be integrally formed with or otherwise provided with longitudinally extending straps 10 which may be bolted or otherwise secured to the frame of the engine. The valve 4 has its plug 5 provided with a port 6 which is normally arranged transversely of the valve casing, so that the said valve is normally closed. The outer face of the valve has its flange or collar provided with a plurality of depressions forming teeth 7, and the said flange is provided, at a suitable point with an enlargement 8 having angular walls 15 which provide stops 9 and 10, the purpose of this arrangement will be presently set forth.

Secured to or integrally formed with the plug 5 is a stem 11, and the said stem, adjacent its juncture with the plug is provided with a spring pressed dog 12, the said dog adapted to co-act with the teeth 7 to securely lock the valve in an open position and to assist in retaining the valve in a closed position as will be presently understood. The stem, at its juncture with the plug 5 is provided with oppositely arranged shoulders or stop members 13 and 14 respectively, and the stop 13 is adapted to 20 engage with the shoulder 9 when the stem and plug are rotated to open the valve, while the stop 14 contacts with the shoulder 10 when the valve is in its closed position. The stem 11 is square or angular in cross 25 section and has one of its sides serrated transversely or otherwise provided with teeth 15.

The numeral 16 designates a throw arm for the stem 11. The throw arm 16 has one 30 of its ends enlarged to provide a head 17, the said head being formed with a bore or opening 18, the walls of which conform to the cross sectional contour of the stem 11. The head is provided with a threaded opening 19 which communicates with its bore, the said opening being adapted for the reception of a headed threaded member 20, and this member 20 is adapted to tightly engage with one of the faces of 35 the stem 11 to bind the arm upon the stem. One of the faces or walls of the bore 18 of the head 17 is formed with teeth 21, and these teeth are adapted to co-actually engage with the teeth 15 of the said stem,

so, when the binding nut 20 properly engages with the stem the throw arm is effectively sustained against longitudinal or lateral movement with relation to the said stem. The throw arm 16 comprises a pair of members 23 and 24 respectively. The upper portion of the member 20 is provided with the head above referred to, and the said arm has one of its faces, preferably its outer face, formed with a rectangular depression 25, the inner wall 26, provided by the said depression, being formed with transverse teeth 27, and the said inner wall is further provided with an elongated slot or opening 28. The member 24 of the throw arm is of a width adapted to be 40 snugly received within the pocket, the said member 24 having its inner face provided with teeth or serrations 29 which engage with the teeth 27. The member 24 has connected therewith a headed threaded member 30, the stem of which passes through the slot 28 and is provided with a suitable washer as well as a securing nut 31. By this arrangement it will be noted that the member 24 may be adjusted vertically of the member 23 of the throw arm 16, and from the arrangement previously described the said throw arm may be adjusted longitudinally of the stem 11 of the valve. The lower extremity of the member 24 has one of its edges curved, as indicated by the numeral 32.

As illustrated in Fig. 2 of the drawings the stem 11 is arranged transversely of the engine and projects a desired distance beyond the track over which the train passes to permit of the throw arm 16 being disposed to the outer sides of the track. The throw arm, when properly adjusted upon the valve stem 11, has its curved end disposed in the path of contact with a striker arm 33. This arm 33 is slidably mounted within a suitable housing 34 that is secured preferably to one of the ends of the ties which project beyond the rails. In the preferred construction of the striker arm and housing, the said arm 33 comprises a substantially rectangular member, the upper edge of which being rounded, as at 35, and the inner end of the said arm is bifurcated as at 36. The housing 34 is constructed of some heavy metal, and comprises a body 37 having side flanges 38, the said flanges being sufficiently spaced to engage with the opposite sides of a tie 39, while the lower face of the said housing between the flanges rests upon the upper face of the tie 39. The flanges 38 are provided with suitable openings for the reception of securing elements, preferably in the nature of lag screws 40, and the sides of the housing, above the flanges 38 are preferably beveled or inclined toward each other, as indicated by the numerals 41.

The upper face of the housing is horizontally straight, and is centrally provided with a substantially rectangular depression or channel 42 which forms a passage for the throw arm 33. The lower wall of the passage 42 is provided with transversely arranged depressions 43 for the reception of anti-frictional rollers 44 upon which the lower edge of the arm 33 rests, and whereby the said arm may be slid within its passage-way at a minimum amount of friction.

The numeral 45 designates a removable top for the housing. This top member 45 has its lower face centrally formed with a longitudinally extending groove or depression 46, the same providing a rounded wall which corresponds to the shape of the rounded upper edge of the throw arm 33. The top 45 is recessed to provide a lubricant chamber 47, the said chamber having its lower wall formed with a plurality of ports 48 which communicate with its depression 46, and thus deliver the lubricant centrally of the upper rounded edge of the arm 33, so that the said lubricant will flow to the opposite sides of the arm as well as to the bottom wall of the passage 42. It will thus be noted that both the sides and top and bottom of the striker arm are properly lubricated, so that a free movement of the said arm is assured. The lubricant chamber is closed by a hinged cap 49, the said cap being sustained in such a closed position through the medium of a suitable spring catch 50. The top 45 is provided with a plurality of bolt openings disposed adjacent its opposite longitudinal sides which are adapted to align with threaded openings in the top of the housing, the registering openings being adapted to receive removable securing elements in the nature of headed screws 51.

Pivotedly secured within the bifurcated end of the striker arm 33 is a rod 52 which has its free end pivotally connected, as at 53, with one of the arms of a bell-crank lever 54. The lever 54 is pivotally secured, as at 55, to a suitable upright 56, the said upright may, if desired, provide one of the walls of a semaphore stand. The bell-crank lever 54 has its arm to which the rod 52 is pivoted provided with a weight 57, and the said weight rocks the bell-crank lever to force the striker arm 33 outwardly of the housing 34 to arrange the same within the path of contact with the throw arm of the valve 4, and it will be thus noted that the said throw arm is normally automatically arranged to operate said valve to cause the automatic application of the brakes to the rolling stock. The free arm of the bell-crank lever may be provided with a rod 58 which has its upper end provided with a slotted enlargement 59, the slot of the said enlargement adapted to receive an offset,

end of a semaphore operating rod 60. It 65 will, of course, be understood that the parts of the device connected with the upright 56, and if desired, the rod 52 as well as the housing 34, may be provided with suitable sheathings which will protect the same from 70 the elements, and, as indicated by the dotted lines, in Fig. 2 of the drawings, a hand-lever 61 may be employed for operating the rod 52 and the striker arm 33. It has also been found desirable to provide the arm 33 75 with an adjustable element in the nature of a collar 62 which is adapted to abut with the outer face of the housing to limit the outward movement of the arm 33 from the said housing, so that the throw of the arm 80 may be thus nicely regulated.

From the above description taken in connection with the drawings, it will be noted that I have provided a simple, cheap, and thoroughly effective device for the purpose 85 intended, one wherein the parts may operate automatically and which will properly apply the brakes when the engineer has either mistaken his signals or has failed otherwise in operating the engineer's valve. 90 It will be further noted that the teeth 7 of the valve 4 are arranged to permit of the spring pressed dog 12 ratcheting over the same when the stem 11 is rotated by the throw arm 16, and also that the said dog 95 will engage with one of the teeth to retain the plug of the stem in such position against accidental rotation, so that it is absolutely necessary that the engineer or locomotive attendant descend from the cab and operate 100 the dog before the stem and plug can be rotated to close the valve before the brakes are relieved and the travel of the train resumed. The weight 57 actuating the striker arm 33 retains the said arm normally 105 within the path of contact of the throw arm 16, and also it will be noted that by providing the valve casing and valve stem with the stops, the rotation of the said stem is limited in either direction. It is also thought 110 that the improvement and its advantages will be apparent to those skilled in the art to which such devices appertain without further detailed description.

Having thus described the invention, what 115 I claim as new is:

In a device for the purpose set forth, a main air pipe, a bleed valve, a pipe connected between the bleed valve and main pipe, the plug of the bleed valve having a 120 co-axially extending stem, a throw arm having a head which is adjustably secured upon the stem, the said throw arm extending at an angle from the stem, the said arm comprising two members, one of which has a 125 rectangular depression in one face of its lower end and an elongated opening, the inner face of the depression being formed

with teeth, the second member having one of its faces formed with teeth and adapted to be received within the depression of the first mentioned member, a bolt connected with the second mentioned member and extending through the slot of the first mentioned member, and a nut for the bolt.

In testimony whereof I affix my signature in presence of two witnesses.

JOHN A. ANTHONY.
